CLAIM

The ornamental design for a vehicle fender as shown and described.

DESCRIPTION

FIG. 1 is a top, left, front perspective view, showing the first embodiment of a vehicle fender showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a top, left, front perspective view, showing the second embodiment of a vehicle fender which is the mirror image of the Fender Support of FIGS. 1-7;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.

Stippling in the drawings represents the three-dimensional contours of the design, and is not intended to indicate surface decoration. The broken lines shown in the drawings depict portions of the vehicle fender that form no part of the claimed design.
